[57] CLAIM

The ornamental design of a hose reel casing, as shown and described.

DESCRIPTION

FIG. 1 is a front perspective view of a hose reel casing;

FIG. 2 is a front plan view thereof;

FIG. 3 is a rear plan view thereof;

FIG. 4 is a left side plan view thereof;

FIG. 5 is a right plan view thereof;

FIG. 6 is a top plan view thereof; and,

FIG. 7 is a bottom plan view thereof.

The broken line showing of portions of the hose reel casing are for illustrative purposes only and forms no part of the claim design.
